UNITED STATES PATENT OFFICE.

GAYLE BURLINGAME, OF COLUMBIA, PENNSYLVANIA.

MOP.

1,402,047.

Specification of Letters Patent. Patented Jan. 3, 1922.

Application filed February 16, 1921. Serial No. 445,445.

To all whom it may concern:

Be it known that I, GAYLE BURLINGAME, a citizen of the United States, residing at Columbia, in the county of Lancaster and State

5 of Pennsylvania, have invented certain new and useful Improvements in Mops, of which the following is a specification, reference being had to the accompanying drawings.

This invention relates to improvements in 10 mop heads.

An important object is to provide a device of this character which may be comparatively cheaply constructed.

A further object of the invention is to provide 15 a mop wherein the attached portions of the yarn or other material employed in constructing the mop are so positioned that they are not brought into engagement with the surface being mopped during the mopping operation in order that extreme wear 20 at these points may be avoided.

To this end the invention consists in the body portion having formed in one side and in the two adjacent ends a continuous groove 25 in which the yarn or other material employed in constructing the mop has its central portion disposed and held in position by wires or other suitable securing mediums.

Other objects and advantages of the invention 30 will become apparent throughout the course of the following description:

In the accompanying drawings, wherein for the purpose of illustration is shown a preferred embodiment of my invention, and 35 wherein like reference characters designate like parts throughout:

Figure 1 is a side elevation of a mop head constructed in accordance with my invention;

40 Figure 2 is a section on the line 2—2 of Figure 1;

Figure 3 is an end elevation of a mop head constructed in accordance with my invention, a portion of the wiping elements 45 being broken away for the purpose of illustration, and

Figure 4 is a longitudinal sectional view partly in elevation thereof.

Referring now more particularly to the 50 drawings, the numeral 10 indicates a body portion having formed in the side thereof a groove 11. The ends of the body portion 10 are provided with grooves 12, preferably of larger size than and communicating 55 with the groove 11. Adjacent the upper ends of the grooves 12, or adjacent that

portion thereof remote from the groove 11, the base of the grooves and body portion is provided with longitudinally extending bores 13.

These bores are adapted for the reception of retaining mediums 14 of wire or some other suitable material. These wires have one end placed in said bores and the yarn or other suitable material employed in constructing the mop, as indicated at 15, is placed beneath the wires and the wires bent against the base of the grooves 12, in which position they are held by means of staples 16 or the like, extending into the body portion at the base of the grooves 12. By this construction the yarn at the ends of the mop is forced into the grooves 12 and securely held therein and has its ends projected without the grooves. The wires 14 are again 75 bent to lie within the groove 11 and the yarn placed therebeneath and the wires driven firmly into the groove 11 so as to draw the central portion of the yarn which is placed about the wires downwardly into the groove 80 11. The staple 17 will preferably engage about both wires 14 which are of sufficient length to extend beyond the center of the groove 11 from the groove 12 in which they are seated. In fact these wires preferably 85 extend to the opposite end of the groove 11 from the groove 12 in which they are attached as indicated at 14^a. The body portion 10 will, of course, be provided with some suitable handle attaching means illustrated in the present instance as the threaded opening 18 formed in the body portion at the opposite side thereof from the groove 11. In the construction of hand brushes and other similar brushes and mops, the wire 90 95 and construction of one end is omitted and the handle is secured to this end.

From the foregoing it will be seen that I have provided a mop in which central or attached portions of the yarn, or other material which form the mop proper, are secreted within the groove formed in the body portion and are, accordingly, fully protected from the rubbing action usually employed in mopping, thereby preventing their destruction at this point which is the point at which the majority of the wear upon a mop occurs. It will likewise be obvious that the construction as hereinbefore set forth is capable of some change without departing 105 from the spirit of my invention. I accordingly, do not limit myself to the specific con-

struction as hereinbefore set forth, except as so limited by the sub-joined claims.

What I claim is:

1. A mop head comprising a body portion provided at one side thereof with a longitudinal groove, said body portion being likewise provided in the ends thereof with end grooves communicating with said first named groove, the body portion at the base of said 5 last named grooves being provided with reduced longitudinally extending bores, pliable securing members having one end disposed within the longitudinally extending bores, said pliable securing members having 10 portions lying within said end grooves and other portions extending longitudinally of the first named groove, wiping elements disposed intermediate said pliable members and said body portion, and means to hold said 15 members pressed against said wiping elements.
2. A mop head comprising a body portion provided at one side thereof with a longitudinal groove, said body portion being likewise provided in the ends thereof with end grooves communicating with said first named groove, the body portion at the base of said last named grooves being provided with reduced longitudinally extending bores, pliable securing members having one end disposed within the longitudinally extending 20 bores, said pliable securing members having portions lying within said end grooves and 25
- 30

other portions extending longitudinally of the first named groove, wiping elements disposed intermediate said pliable members and said body portion, and securing elements engaging about said pliable members and in the body portion within said grooves, the free ends of said pliable portions overlapping. 35

3. A mop comprising a body portion provided at one side thereof with a longitudinal groove, said body portion being likewise provided in the ends thereof with end 40 grooves communicating with said first named groove, the body portion at the base of said last named grooves being provided with reduced longitudinally extending bores, pliable securing members having one end disposed within the longitudinally extending 45 bores, said pliable securing members having portions lying within said end grooves and other portions extending longitudinally of the first named groove, wiping elements disposed intermediate said pliable members and said body portion and securing elements 50 engaging about said pliable members and in the body portion within said grooves, the free ends of said pliable members extending 55 to the end of the first named groove next adjacent the end groove in which the other of said pliable members is attached. 60

In testimony whereof I hereunto affix my signature.

GAYLE BURLINGAME.
